UNITED STATES PATENT OFFICE.

DWIGHT F. KILGOUR, OF LEXINGTON, MASSACHUSETTS.

LUBRICATOR.

1,136,426.

Specification of Letters Patent.

Patented Apr. 20, 1915.

Application filed November 11, 1913. Serial No. 800,389.

To all whom it may concern:

Be it known that I, DWIGHT F. KILGOUR, a citizen of the United States, and a resident of Lexington, county of Middlesex, 5 and Commonwealth of Massachusetts, have invented an Improvement in Lubricators, of which the following description, in connection with the accompanying drawings, is a specification, like characters on the 10 drawings representing like parts.

This invention relates to lubricators for elevator guide rails and other uses and, among other objects, provides a strong, simple device for supplying a proper amount 15 of lubricant to the rail.

The character of the invention may be best understood by reference to the following description of an illustrative embodiment thereof shown in the accompanying drawings 20 ing wherein:

Figure 1 is a side elevation of an illustrative lubricator embodying the invention and shown as applied to an elevator guide rail; and Fig. 2 is a rear elevation of the 25 lubricator shown in Fig. 1.

Referring to the drawing, the illustrative lubricator there shown as embodying the invention comprises a reservoir 1 shown herein as of metal cast into cylindrical form. 30 To permit the filling of the reservoir it is provided with a neck 3 having a cap 5 threaded therein.

To conduct the lubricant from the reservoir to the guide rail or other member to be lubricated, there is provided a wick 7 preferably sufficiently long to extend from the bottom nearly to the top of the reservoir, where it is led through an outlet herein in the form of a short neck 9 secured to the 40 side of the reservoir. The wick projects through this neck and is adapted to engage the guide rail.

To secure the wick in the neck and prevent it from being pushed back into the reservoir in pressing against the rail and also to variably compact the wick fiber within said neck to vary the freedom of flow of the lubricant through the neck, there is provided a screw 11 tapped into said neck and extending a substantial distance into the latter.

The reservoir preferably is pivotally mounted so as to tilt toward the member to be lubricated. To this end the reservoir is 55 provided with a lug 13 depending centrally

from the bottom thereof and received between ears of a support, herein in the form of a slide plate 15. A pin 17 passes through registering holes in said lug and ears, thereby providing a fulcrum permitting the free 60 tilting of the reservoir.

By the construction described the brunt of the weight of the reservoir is borne by the support. For the best lubrication, the wick should be pressed lightly against the 65 rail to prevent undue compacting of the wick fibers such as might retard the proper feeding of the lubricant therethrough. The light pressure for the wick is also important to prevent the same from wearing out too 70 rapidly with the necessity of frequent adjustment and replacement. The reservoir, while pressed lightly against the rail, should be free to rock backward and yield in response to any irregularities which might 75 exist in said rail and also to take up lost motion due to the play between the elevator car and the rail in the course of its travel.

In my copending application is shown a 80 lubricator which is rocked laterally with the desired nicety of pressure by gravity. This is highly satisfactory for certain uses, but when used on ship the motion of the ship is liable to throw the lubricator out of 85 contact with the elevator guide rail or member to be lubricated.

One of the objects of this invention is to provide a lubricator which will not be subject to this objection. To this end the 90 reservoir is provided with a helical spring 17 of light gage wire and considerable length, said spring being confined between the reduced end of an arm 19 projecting rearwardly from the reservoir and a stud 95 21 projecting upwardly from said slide plate 15. The point of application of the spring to the reservoir is offset a substantial distance from the fulcrum point of the reservoir and therefore the light spring gains 100 mechanical advantage for rocking the reservoir toward the member to be lubricated. The spring being of considerable length and of light gage wire may experience a substantial compression contracting the coils 105 without materially increasing the pressure of the spring. As a result the spring will exercise a substantially uniform pressure throughout the slight tilting movements of the reservoir in the course of its movement 110

along the guide rail and maintain a desired substantially uniform nicety of pressure of the wick against the rail.

The lubricator is shown herein as mounted on a usual shoe 23 which is connected to the elevator car. In some cases it may be desired to adjust the reservoir toward or from the rail to different fixed positions according to different conditions. To permit this, the support slide 15 is provided with a depending rib 25 received in the slot of a forked bracket 27 secured to said shoe. To clamp the support slide 15 in a different position of adjustment relative to said forked bracket there is provided a screw 31 having a washer interposed between its head and the under face of the forked bracket and somewhat larger than the slot in said bracket. When this screw is set up it will 20 tightly draw the slide plate 15 and clamp the same to the bracket.

By my invention there is provided a lubricator having many advantages. The reservoir is always rocked to press its wick lightly against the member to be lubricated with the desired nicety of pressure. In marine use if the motion of the ship should rock the wick momentarily out of engagement with said member, the spring would 30 return the same promptly to said member. The wick in extending upward and out of the lubricant draws the latter up by capillary attraction and therefore prevents an excessive and wasteful feeding of the lubricant and contributes to the supplying of the proper amount of lubricant for the best lubrication and economy.

Having described one illustrative embodiment of the invention without limiting 40 the same thereto, what I claim as new and desire to secure by Letters Patent is:

1. A lubricator comprising in combina-

tion, a support; a reservoir fulcrumed thereon and provided with a wick outlet for a lubricating wick leading from within said reservoir, the latter being arranged with the brunt of its weight on said support, and spring means for pressing the reservoir toward a member to be lubricated.

2. A lubricator comprising in combination, a support; a reservoir fulcrumed thereon and provided with a wick outlet for a lubricating wick, said reservoir being arranged with the brunt of its weight on said support, and spring means connecting said reservoir and support for pressing the former toward a member to be lubricated with light engaging contact.

3. A lubricator comprising in combination, a support; a reservoir fulcrumed thereon and provided with a wick outlet for a lubricating wick; an arm projecting from said reservoir; and a helical spring interposed between said arm and said support for tilting said reservoir toward a member to be lubricated.

4. A lubricator comprising in combination, a support; a reservoir fulcrumed thereon and provided with a wick outlet for a lubricating wick; and a spring connecting said reservoir with said support for tilting said reservoir to present its wick in light engaging contact with a member to be lubricated, said support having provision for permitting the adjustment of said reservoir toward or from said member to different fixed positions.

In testimony whereof, I have signed my name to this specification, in the presence of two subscribing witnesses.

DWIGHT F. KILGOUR.
